UNITED STATES PATENT OFFICE.

FREDERICK J. HERMANN, OF LUDINGTON, MICHIGAN, ASSIGNOR TO STAR WATCH
CASE CO., OF LUDINGTON, MICHIGAN.

DESIGN FOR A WATCHCASE.

60,142.

Specification for Design.

Patented Jan. 3, 1922.

Application filed January 31, 1921. Serial No. 441,486. Term of patent 7 years.

To all whom it may concern:

Be it known that I, FREDERICK J. HERMANN, a citizen of the United States, residing at Ludington, in the county of Mason and State of Michigan, have invented a new, original, and ornamental Design for Watchcases, of which the following is a specification, reference being had to the accompanying drawing, forming part thereof, in which—

Figure 1 is an edge elevation of a watch case showing my new design, and

Figure 2 is a side view thereof, and

Fig. 3 is a view in edge elevation, showing the opposite edge of the watch case illustrated in Fig. 1.

I claim:

The ornamental design for a watch case, as shown.

FREDERICK J. HERMANN.
